DESIGN FOR A KEYBOARD FOR CHECK WRITERS

Ole Slettevold, Chicago, Ill., assignor to The Hedman Manufacturing Company, Chicago, Ill., a corporation of Illinois

Application February 15, 1934, Serial No. 50,739

Term of patent 14 years

To all whom it may concern:

Be it known that I, Ole Slettevold, a subject of the King of Norway, residing at Chicago, in the county of Cook and State of Illinois, have invented a new, original, and ornamental Design for a Keyboard for Check Writers, of which the following is a specification, reference being had to the accompanying drawing, forming part thereof.

The drawing shows a figure representing a perspective view of a keyboard for check writers showing my new design.

I claim:

The ornamental design for a keyboard for check writers, as shown.

In witness whereof, I hereunto subscribe my name, this 10th day of February, 1934.

OLE SLETTEVOLD.
